DESIGN FOR A FORAMINATED DIE

Claude C. Hall, Portland, Oreg.

Application September 22, 1937, Serial No. 71,727

Term of patent 14 years

To all whom it may concern:

Be it known that I, Claude C. Hall, a citizen of the United States and a resident of the city of Portland, Multnomah County and State of Oregon, have invented a new, original, and ornamental Design for a Foraminated Die, of which the following is a specification, reference being made to the accompanying drawing, which forms a part thereof.

Figure 1 is a rear perspective view of a foraminated die embodying my new design;

Figure 2 is a front perspective;

Figure 3 is a rear elevational; and

Figure 4 is a cross-sectional view thereof, taken substantially through the central portion of the article.

The perforations shown extending through the side walls are continued throughout these walls like in Figures 1, 2, and 3.

I claim:

The ornamental design for a foraminated die, substantially as shown and described.

CLAUDE C. HALL,
